(57) **CLAIM**

The ornamental design for a soap dispenser, as shown and described.

DESCRIPTION

FIG. 1 is a top perspective view of a soap dispenser showing our new design;

FIG. 2 is a right side view thereof; and,

FIG. 3 is a front view thereof.

The left side view is a mirror image of the right side view. The rear view is the same as the front view, except that the handle is not included.

The bottom view is unornamented.
